PENDLETON W. MURRAY, OF OMAHA, NEBRASKA

RADIATOR

Application filed July 9, 1929. Serial No. 376,976.

The invention relates to radiators of the type used in connection with motor driven vehicles and has for its object to provide a device of this character formed in sections whereby the radiator may be easily assembled or disassembled for shipment and storage purposes as well as repair purposes.

A further object is to form the radiator from an upper chambered section, an intermediate tube carrying section and a lower chambered section and to detachably connect said sections together whereby they may be easily disassembled for repair purposes and easily assembled.

15 A further object is to provide the intermediate section with horizontal tubes, the upper ends of which have pipe connections with the upper section of the radiator and the lower pipe sections communicate with the lower radiator section. Also to provide U-shaped pipe couplings connecting the ends of the horizontal pipes and disposed in chambers in the sides of the intermediate section.

20 A further object is to provide vertically disposed pipes interwoven in the horizontal pipes and connecting the upper and lower radiator sections and through which the circulating water passes for cooling purposes.

25 A further object is to provide the ends of the horizontal pipes with head engaging plates and to provide plates within the side chambers of the intermediate section and engaging heads of a U-coupling and bolts extending through said plates and the sides of the intermediate section for forcing the heads in the water tight engagement with each other.

30 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

35 Figure 1 is a view in elevation of the radiator.

Figure 2 is a vertical transverse sectional view through the radiator.

Figure 3 is a vertical transverse sectional view through the radiator taken on line 3—3 of Figure 2.

40 Figure 4 is a horizontal sectional view through one side of the intermediate section.

Referring to the drawing the numeral 1 designates the upper section of the radiator, 2 the intermediate section and 3 the lower section. The opposite sides of sections 1, 2 and 3 are provided with lugs 4 through which bolts 5 extend for securely attaching the sections together and at the same time allowing the radiator to be easily and quickly assembled and disassembled for repair purposes. The upper section 1 is provided with a conventional filling opening 6 and has a chamber 7 therein into which water from the engine passes through the intake port 8. The lower section 3 is provided with a chamber 9 into which the water passes after leaving the intermediate section 2 and is discharged through the discharge port 10 to the engine jacket in the usual manner.

45 The opposite sides of the intermediate section 2 are formed from channeled members 11, in which are slidably mounted plates 12, which may be soldered at 13 for forming watertight chambers 14, and threaded through said plates 12 are securing bolts 15, the inner ends of which are threaded through the plates 16 also slidably mounted within the channeled members 11, therefore it will be seen that when the bolts 15 are 50 rotated, the plates 16 will be forced inwardly, thereby forcing the heads 17 of the horizontal tubes 18 and the heads 19 of the U-shaped connections 20 into close watertight engagement whereby fluid from the chamber 7 will take a zig zag course downwardly and be discharged through the ports 21 in one of the chambers 14 and will then pass downwardly through the port 22 into the chamber 9, thereby insuring a cooling of the liquid. 55 The upper ends of the upper tubes 18 are provided with L connections 23 with the upper section 1 of the radiator.

60 To further insure the cooling of the liquid vertically disposed tubes 24 are provided,

which tubes are interwoven with the transverse tubes 18 as clearly shown in Figures 1 and 3 and have their upper ends in communication with the chamber 7 of the upper section 1 at 24a where they pass through the wall 25 connecting the side members of the intermediate section and in communication with the chamber 9 of the section 3 at 26 where they pass through the lower wall 27 forming the bottom of the intermediate section 2. Walls 25 and 27 may be welded or otherwise secured to the ends of the side members 11 of the intermediate sections when forming the sections. It will be noted that the plates 16 are disposed outside the side members 11, therefore it will be seen that when the bolts 15 are removed, the headed members 17 and 19 will allow the tubes to be removed and replaced.

From the above it will be seen that a radiator structure is provided which is simple in construction, formed from a plurality of sections which may be easily and quickly assembled or disassembled for repair purposes, and a combination of horizontal and vertical tubes are used through which the fluid flows thereby insuring a maximum cooling efficiency and that the tubes extending in one direction are interwoven with the tubes extending in the other direction, thereby insuring maximum length of tubes. The interwoven tubes which extend vertically as well as the other tubes may be formed from any kind of material, and applicant does not limit himself in this particular.

The invention having been set forth what is claimed as new and useful is:

1. A radiator comprising an upper section having a chamber therein into which water enters, a lower section having a chamber therein into which water enters and from which water is discharged, an intermediate section, said intermediate section comprising side chambered members, horizontal tubes carried by the intermediate section, vertical tubes carried by the intermediate section and communicating with the chambers of the upper and lower sections, U couplings connecting the ends of adjacent horizontal tubes thereby forming zig zag conduits, the upper horizontal tubes having one of their ends connected to the upper section, the ends of the horizontal lower tubes discharging into the lower section and said vertical tubes interwoven in the horizontal tubes and forming communication between the chambers of the upper and lower sections.

2. A radiator comprising an upper section having a chamber therein, a chambered lower section, an intermediate section, said intermediate section comprising chambered channeled side members, horizontal tubes carried by the intermediate section, plates adjacent the ends of said tubes, the ends of said tubes extending through said plates, heads carried

by said tubes and engaging the plates, plates within the channeled members, bolts cooperating with said plates for forcing said plates towards each other, U couplings carried by the plates within the channeled members, heads carried by said couplings and engaging the heads of the tubes, said couplings connecting the tubes whereby zig zag tubes are formed communicating with the chambers of the upper section and the lower section.

3. A radiator comprising an upper chambered section, a lower chambered section, an intermediate section, said intermediate section having side channeled members, plates within the channeled members, plates within the intermediate section, horizontal tubes extending through one of the latter plates at either side of the intermediate section, heads carried by said tubes, U couplings carried by the other plates and disposed within the channeled members, heads carried by the U couplings and engaging the heads of the tubes whereby zig zag tubes are formed connecting the chambers of the upper and lower sections, bolts extending through the channeled members and cooperating with the plates whereby said heads are forced together and vertical tubes interwoven in the horizontal tubes and connecting the chambers of the upper and lower sections.

In testimony whereof he hereunto affixes his signature.
